UNITED STATES PATENT OFFICE.

CHARLES S. BREWER, OF HERKIMER, NEW YORK, ASSIGNOR TO STANDARD FURNITURE COMPANY, OF HERKIMER, NEW YORK, A CORPORATION OF NEW YORK.

DESIGN FOR A CARD PLATE OR HOLDER.

SPECIFICATION forming part of Design No. 35,917, dated May 20, 1902.

Application filed March 29, 1902. Serial No. 100,622. Term of patent 14 years.

To all whom it may concern:

Be it known that I, CHARLES S. BREWER, a citizen of the United States, residing at Herkimer, in the county of Herkimer and State of New York, have invented and produced a new and original Design for Card Plates or Holders, of which the following is a specification.

My present invention pertains to a novel design for card plates or holders.

The design will be best understood upon reference to the annexed drawings, wherein—

Figure 1 is a face view of the plate or holder, and Fig. 2 a side elevation thereof.

The plate or holder comprises two long members A A' and two shorter members B B', each

member having formed on its face beads or flutings C. Said beads or flutings are wider at the center of each member, tapering toward their ends, the ends passing or vanishing into the rounded projections or knobs D, which appear at the four corners of the plate.

Having thus described my invention, what I claim is—

The design for a card plate or holder, substantially as shown and described.

In witness whereof I hereunto set my hand in the presence of two witnesses.

CHARLES S. BREWER.
